UNITED STATES PATENT OFFICE.

JOHN COLOMBO, OF AUBURN, NEW YORK.

TORPEDO NETTING.

Application filed February 5, 1926. Serial No. 86,221.

This invention relates to improvements in torpedo nets, designed to be detachably applied to battleships and other sea-going vessels, and has for its object to provide a 5 novel, simple and effective netting adapted to be mounted on the opposite sides of a vessel and partially submerged, for preventing torpedoes from reaching and injuring the vessel. A further object is to provide 10 a net-work composed of stout flexible metal strands or links, which is mounted upon and interwoven with a plurality of stays or posts; said stays being detachably supported by sockets formed in the armour or other 15 external surface of the hull of the vessel, and said stays being held in extended position horizontally by means of said sockets supplemented by cables that preferably extend continuously around the hulls in horizontal 20 planes, and the cables being held from gravitating and from sagging by suitable fasteners or hangers, which may be disposed at the bow, the stern, as well as at intervals along the opposite sides of the hull. And a 25 particular object is to provide a torpedo net of the class that may be readily and quickly applied to a vessel during times of war, and which may be removed, rolled up and stored on board the vessel during times of peace. 30 I attain these objects by the means set forth in the detailed description which follows, and as illustrated by the accompanying drawing, in which—

Figure 1 is a plan outline of the hull of a vessel, to which my torpedo net is applied. Fig. 2 is a side elevation of the same; showing the net disposed in a manner to protect the vessel for a considerable distance above and below the waterline; also showing convenient means for securing the netting to the hull. Fig. 3 is an enlarged broken section; showing the construction and arrangement of the stays which support the net. And Fig. 4 is a similar view showing a modification of the parts illustrated in Fig. 3.

In the drawing, 2 represents conventionally the hull of a vessel, 3 the bow, 4 the stern, and 5 the gunwale.

My improved torpedo net preferably comprises 2 similar sections, as 6—6', which are designed to protect the corresponding sides of the hull from attack and injury by torpedoes, mines, and the like. The net proper preferably consists of a relatively coarse weaving of steel wire-cable stock of suitable

gauge, comprising strands 6^a which may be disposed diagonally, and similar horizontal and vertical strands 6^b—6^c. The wires 6^a—6^b and 6^c are all preferably interwoven with rings 7, and the nets 6—6' are preferably supported at a suitable distance from the hull 2, by means of horizontal stays or posts 8, which preferably decrease in length from amidships towards the bow and stern, 65 as best seen in Fig. 1.

In the preferred construction, the stays 8 are made of relatively heavy steel or iron tubing 8', as shown in Fig. 3. The inner ends of these tubes are preferably provided 70 with short solid metal cores 8^a which are rigidly applied to the tubes, and project tenon-like beyond the ends of the tubes, as at 8^b and these tenons are preferably seated in sockets 2', which may be formed 75 in the armour or other material of the hull, as shown in Figs. 1 and 3. Satisfactory stays, as 9, may be made from solid metal having their inner ends reduced, as at 9', 80 for insertion into the sockets 2', or into 85 sockets 10 formed in plates 10' which may be bolted or otherwise permanently secured to the outer surface of the hull 2, as shown in Fig. 4. The outer or free end of each stay 8 is preferably provided with a loop 8^c, which may be an integral part of a cylindrical plug or core 8^d which is rigidly applied to the tube 8' the same as the core 8^a. These loops 8^c are provided primarily for 90 facilitating the passing therethrough of a relatively heavy cable, as 12, which affords the main support for the stays after they have been placed in the operative position shown in Figs. 1, 2 and 3. The cable 12 is 95 preferably applied to the topmost row of stays and extends around the entire hull and its ends may be secured in any suitable manner (not shown) at either the bow or stern, at which points the cable passes through relatively heavy loop-supports 100 13—13', which are preferably rigidly secured to the hull, as shown at 13^a, in Figs. 1 and 2. In order to prevent the medial portions of the cable 12 at the opposite sides of the hull from sagging, the alternate 105 vertical strands 6^c preferably extend upwardly and are suitably secured to the gunwale 5, and for this purpose the latter is provided with studs or fasteners 14, which are engaged by rings 7' carried by the top 110 ends of the said strands. Similar rings 7^a are also secured to the strands 6^c, through

which the cable 12 passes, the rings 7^a preferably being arranged to align with the loops 8^c of the stays. In the preferred construction, the stays 8 of the top row are 5 preferably larger and stouter than the stays of the second and third row, but the middle and lowermost rows of stays may be of the same size and strength. The alternate vertical strands 6^c of the nets preferably connect with the loops 8^c of the several rows of stays, as shown in Figs. 2 and 3. Smaller continuous cables 12' and 12^a are then passed through the loops 8^c of the middle and lower rows of stays, and these cables 10 are preferably supported at the bow and stern by similar loop-support 13—13'. The tenons 8^b are preferably loosely set in the sockets 2', and the stays therefore depend upon the cables 12—12'—12^a and also the 15 vertical strands 6^c, for holding them in their sockets. By this construction and arrangement the nets 6—6' may be readily and quickly applied to and removed from the hull by the seamen. In times of peace the 20 nets 6—6' may be rolled up and stowed away in the bunkers or may be otherwise conveniently disposed of on board the vessel. The triangular openings in the nets indicated at 6^d, are preferably considerably 25 smaller than the diameter of the torpedoes in common use, so that the torpedoes upon approaching the vessel may be prevented from penetrating the nets and making contact with the hull. In case of the detonation 30 of a torpedo that has been stopped by the net, the force of the explosion can not seriously injure the hull of the vessel. When orders are given to apply my improved nets the 35 seamen unroll and lower the nets over the sides of the vessel while other hands descend 40 on ladders and insert the stays in their proper sockets. While this is being done the cables 12' and 12^a if not already attached, may be applied and tightened, and 45 the strands 6^c at the same time may be secured to the fastenings 14, as explained.

Having thus described my invention, what I claim, is:—

- 50 1. Means for protecting ships against torpedoes, mines and the like, comprising a woven wire net arranged in similar sections adapted to be draped along the opposite sides of the hull of the ship, stays of different length extending between the net and the hull, and the stays having loops at their free ends, cables encircling the hull and passing through the loops of the stays, loop-supports mounted at the bow and stern of the hull and aligning with the stays for preventing the gravitation of the cables, and means interposed between the cables and the gunwale for preventing sagging of the cables and net between the bow and the stern.
- 55 60 65 2. A torpedo net for ships, comprising a

number of oblique, vertical and horizontal strands of wire and a plurality of rings interwoven to form sections adapted to be draped loosely along the opposite sides of the hull of the ship and extending above and below the normal waterline, stays interposed horizontally between the net and the outer surface of the hull for supporting and spacing the net from the hull, the said stays being arranged in parallel horizontal rows, 70 cables encircling the hull and engaging the free ends of the stays, and certain of the vertical strands of the net being arranged to support the medial portions of the cable at the opposite sides of the hull for preventing 80 sagging of the cables.

3. A torpedo net for ships, comprising oblique vertical and horizontal strands of wire woven in oblong sections adapted to protect the opposite sides of the hull of the ship, stays disposed in parallel horizontal rows located above and below the normal waterline for supporting the net at a distance from the sides of the ship, said stays having loops at their outer ends, cables encircling the hull horizontally and passing through the loops of the stays, loop-supports mounted at the bow and also at the stern for supporting the said cables beyond the 90 ends of said sections and alternate vertical strands of the net engaging the topmost cable and extending upwardly and being fastened to the gunwale for supporting the 95 portions of the cable extending between the bow and the stern.

4. The combination of a ship's hull having sockets formed in horizontal rows above and below the waterline and having fasteners at spaced intervals along the gunwale, of a torpedo net comprising similar sections adapted to be draped around the opposite sides of the hull, said net comprising oblique, vertical and horizontal wires, the alternate vertical wires being of different length, stays detachably supported by the sockets of the hull and having loops to which the oblique and the shorter vertical wires are attached, rings interwoven with the oblique, vertical and horizontal wires, the longer vertical wires extending above the topmost row of stays and engaging the said fastenings, and cables encircling the hull and passing horizontally through the loops of said stays and also through rings connecting with the said longer vertical wires for supporting the sections at the opposite sides of the hull.

5. The combination with the hull of a vessel having sockets arranged above and below the normal waterline, and loop-supports mounted on the bow and stern of the hull, of a torpedo net comprising a plurality of wires interwoven with a plurality of rings, stays of different length supported by said sockets and extending horizontally 120 125 130

for spacing the net from the hull, said stays decreasing in length from amidships toward the bow and stern and having loops at their outer ends, continuous cables encircling the hull and passing through said loop-supports and also through the loops of each row of stays, and certain of said rings and a portion of said wires extending above the topmost cable and being fastened to the gunwale for preventing sagging of the cables between 10 the bow and stern.

In testimony whereof I affix my signature.

JOHN COLOMBO.
